UNITED STATES PATENT OFFICE

JOHN J. FLANIGAN, OF OAK PARK, ILLINOIS

DESIGN FOR A STAND FOR A DUPLICATING MACHINE OR THE LIKE

Application filed July 11, 1931. Serial No. 40,500. Term of patent 14 years.

To all whom it may concern:

Be it known that I, JOHN J. FLANIGAN, a citizen of the United States, residing at Oak Park, in the county of Cook and State of Illinois, have invented a new, original, and ornamental Design for a stand for a duplicating machine or the like, of which the following is a specification, reference being had

to the accompanying drawing, forming a part thereof, in which the figure is a perspective view showing my new design.

I claim:

The ornamental design for a stand for a duplicating machine or the like as shown.

JOHN J. FLANIGAN.
